CLAIM

The ornamental design for a jewelry organizer, as shown and described.

DESCRIPTION

FIG. 1 is a perspective view of the jewelry organizer of the instant invention;

FIG. 2 is a front view thereof;

FIG. 3 is a top view thereof; and,

FIG. 4 is a left side view, the right side view being a mirror image thereof.

The broken lines showing in FIG. 3 are for environmental purposes only and form no part of the claimed design.
